UNITED STATES PATENT OFFICE.

FRANCIS L. BITTLES, OF WEST ORANGE, NEW JERSEY.

DESIGN FOR A BOX OR SIMILAR CONTAINER.

Application filed April 10, 1926. Serial No. 17,246. Term of patent 3½ years.

To all whom it may concern:

Be it known that I, FRANCIS L. BITTLES, a citizen of the United States, residing at West Orange, in the county of Essex and State of New Jersey, have invented a new, original, and ornamental Design for Box or Similar Container, as shown, of which the following is a specification, reference being had to the accompanying drawing, forming part thereof.

The figure is a plan view of a box or similar container showing my new design.

I claim:

The ornamental design for a box or similar container as shown.

In testimony whereof I have hereunto set my hand on this 23rd day of March A. D., 1926.

FRANCIS L. BITTLES.
